(57) **CLAIM**

The ornamental design for a hot air device, as shown and described.

DESCRIPTION

FIG. 1 is a right side elevational view of a hot air device showing our design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof; and,

FIG. 7 is a front perspective view thereof.

The broken lines depict portions of the hot air device in which the design is embodied that are not considered part of the claimed design.
